This invention relates to forming logical operations.

Many pulse operating circuits are used for forming logical operations. Such circuits may use dynamic storage devices for use and the like. It is difficult to operate at frequencies when number of these pulse connected to form large logic electronic computer.

The difficulties associated with logic operations are largely eliminated in logic oscillators. A variety of logic oscillators are described in an article, "Digital Computing Elements and Oscillation" by E. Goto, in the August 1959, pages 13-18. The oscillator consists of a tuned circuit including a nonlinear element, and which has a frequency approximately twice the frequency of the tuned circuit. A variation of the non-linear element produces an oscillatory condition in the second sub-harmonic. The sub-harmonic voltage components are relatively displaced in phase condition of the circuit at the time harmonic oscillation starts.

Provision must be made for switching the circuit from one condition to the other if the device is to be used as a logic element. Substantial energy is required to switch the one phase condition to the other. This may come by periodically quenching the circuit and applying a small control voltage to determine the time of oscillation each time that it re-starts.

Although the parametron is basically a wave device, the necessity for periodic switching introduces the difficulty of obtaining the switching associated with pulse operation. Monic oscillation takes an appreciable time to build up to a uniform amplitude and then the voltage to decay. A time is required to provide an indication of the output of the circuit. Thus, the maximum switching time must be only a sixtieth, or less, of a second. Furthermore, all the output power must be taken from the exciting source, since the circuit

ence, a substantial amount of power frequency is required to operate a logical circuit consisting of interconnected parametrons. An object of the invention to provide an improved logic circuit employing active elements, which operates monic of a driving frequency.

According to the invention an electrical logic circuit includes a pair of active circuit elements adapted to operate in an operating region of negative resistance, a pair of reactance elements of one sign connected in series with the pair of active elements, a reactance element of opposite sign connected to the junction of the pair of active elements and to the junction of the two reactance elements, the three reactance elements forming an effective tuned circuit, driving to the tuned circuit a sinusoidal voltage having a frequency substantially twice the resonant frequency of said tuned circuit, means for deriving from the pair of active elements a voltage across the pair of active elements which is at said resonant frequency and which is either one of two phases relatively displaced, and means for applying an input signal to the active elements to determine the logic signal.

The invention will now be described, by way of reference to the accompanying drawing showing a circuit diagram of a logic circuit employing

the invention. A sinusoidal driving voltage source 1 applies a sinusoidal driving voltage to a resistor 2 to a pair of tunnel diodes 3 and 4. A pair of inductors 5 and 6 and a capacitor 7 are connected in parallel with the two tunnel diodes. The capacitor 7 has a negligible reactance at the frequency of the driving voltage so that the voltage across it is substantially at zero R.F. potential. A D.C. voltage from a source 20 is applied to a point between a supply terminal 8 and the junction of the two tunnel diodes via the inductors 5 and 6 and the capacitor 7 preventing the short circuiting of the supply.

A resistor 9 is connected between the junction of the two tunnel diodes 3 and 4 and the junction of the two inductors 5 and 6. The tunnel diodes are biased in the forward direction by the D.C. voltage applied to the terminal 8 and therefore have a relatively low resistance, for example, of 50 ohms, for example. The tunnel diodes have a substantial shunt capacity of, for example, 100 microfarads. The R.F. source 1 may typically operate at a frequency of 250 mc./s. At this frequency, the reactance of the shunt capacity of the tunnel diode is approximately 100 ohms. Since the reactances of the shunt capacities of the capacitor 7 are relatively small, an approximate R.F. equivalent circuit is that of the two inductors 5 and 6 connected in parallel across the capacitor 9. The two inductors 5 and 6 and the capacitor 9 therefore form an effective tuned circuit with a resonant frequency determined by the value of the capacitor 9 and the reactance of the two inductors in parallel. The reactance of the capacitor 9 and the inductors 5 and 6 are such that the resonant frequency is substantially one-half the frequency of the driving voltage.

The voltage/current characteristic of a tunnel diode is essentially N-shaped. At low voltages the diode behaves as a positive resistance of the order of 50 ohms, the current increasing fairly linearly to a peak of 5 milliamperes at 0.1 volt. As the voltage is further increased, the diode enters a negative resistance region until the current has fallen to a minimum of about .75 milliampere at 0.45 volt. A second positive resistance region follows, so that a voltage of 0.6 volt again produces a current of 5 milliamperes.

It will be appreciated that these numerical values relate to a particular type of tunnel diode and that other type of tunnel diode will have different relative values of current and voltage, but that the general form of their voltage/current characteristic is the same.

It is a feature of devices possessing this N-shaped characteristic that they may be switched very rapidly from a point in the first positive resistance region to a corresponding point of equal current in the second positive resistance region, and vice versa. The R.F. driving voltage controls this switching in the present circuit. As the voltage across the pair of tunnel diodes increases from the start of the first positive half-cycle of the driving voltage, it reaches a value sufficient to maintain one diode in the second positive resistance region and the other in the first positive resistance region. Assume that the diode 3 switches to the second region, then both diodes may be passing approximately 5 milliamperes, but the voltage across the diode 3 will be 0.6 volt and that across the diode 4 will be 0.1 volt. Prior to this, the voltage was divided equally between the two diodes, if they have similar characteristics. The driving voltage will reach a maximum and will then fall towards zero. As the drive voltage decreases, it will fall below the value necessary to maintain the diode 3 in the second region. Thus, the positive half cycle of the driving voltage will produce a positive going voltage pulse across the diode 3 and a negative going voltage pulse across the diode 4. These voltage pulses shock excite the effective tuned circuit, formed by the inductors 5 and 6 and the capacitor 9, at its natural resonant frequency. The negative half cycle of the driving voltage opposes the D.C. voltage applied to the diodes from terminal 8, so that the diodes are not switched. During the next positive half cycle, the driving voltage will again be sufficient to cause switching of the diodes. However, the tuned circuit was shock excited during the previous positive half cycle, so that current is still flowing in the tuned circuit. The current flows in opposite directions in the two inductors and the directions are such that a larger net positive voltage appears across the diode 4 than across the diode 3. Consequently, the diode 4 switches to the second region when the driving voltage increases to a sufficient value. The current in the tuned circuit will have reversed when the next positive half cycle of the driving voltage occurs so that the diode 3 will switch. The diodes will continue to switch alternately on the positive half cycles of the driving voltage as long as the driving voltage is maintained, and the tuned circuit will be driven at the sub-harmonic frequency.

A balanced coupling to the tuned circuit is provided by coils 10 and 11 which are coupled to the inductors 5 and 6, respectively. The coils 10 and 11 are connected so that the induced voltages are additive and a sub-harmonic output voltage will be available at terminal 12 as long as the tuned circuit is driven. The phase of this output will be determined by which of the two positive resistance regions each of the diodes 3 and 4 adapts during the first positive cycle of the driving voltage, i.e., the output voltage will be either in one phase, or in an opposite phase, and once a particular mode is established it is self-sustaining. The phase of the output may therefore be determined by applying a small control voltage to the junction of the two tunnel diodes, to unbalance the voltages across them, during the initial application of the driving voltage. The control voltage may be a sub-har-

monic output derived from another similar logic circuit which is applied to an input terminal 13, and is fed to the junction by a coupling capacitor 14. The output coils, such as the coils 10a, 11a, and 10b, 11b, of other logic circuits may be connected in series and to the terminal 13. The majority of signals which have a common phase will then cause the circuit to lock to that phase. A D.C. signal from a control source 21, which may be the output from a resistor majority logic circuit, may be applied directly to the junction of the diodes as a control signal, the polarity of the signal determining which diode is switched first.

The driving frequency source 1 may be modulated by a square wave from a modulation source 22 to allow the control signals to be effective, in a similar manner to a parametron. A chain of the tunnel diode logic circuits may be operated by using two or three driving sources with different phases for the modulation frequency, successive circuits being driven from different phases.

The control voltages may also be made effective by sine wave modulation of the driving source 1. This is possible because of a hysteresis effect in the switching characteristic. In order to switch the circuit from a quiescent state to a locked phase state, the voltage across one of the tunnel diodes consisting of the sum of the D.C. voltage across that diode, due to the source 20, the voltage from the driving source 1 and any applied control voltage, must exceed the switching voltage of that diode. However, once the circuit is in the locked phase state, the sub-harmonic voltage is also present and it is always adding to the other voltages across that diode which is switched. Consequently, once the circuit is operating in the locked phase state, the amplitude of driving voltage necessary to keep it operating is smaller than is the amplitude needed to switch it. The operating conditions may be selected so that the mean operating point of the diodes lies between the switching and maintaining voltages, then less than 100 percent sine wave modulation of the driving voltage provides sufficient voltage variation to switch the circuit alternately between the quiescent and locked phase states.

It will be apparent that the R.F. driving source 1 acts primarily as a switching voltage source which controls the relative distribution of the applied D.C. voltage between the two tunnel diodes. Consequently, a substantial part of the output power, which is available at terminal 12, is drawn from the D.C. source. This greatly reduces the power required from the R.F. source to provide a given output power. This is a major advantage, since the generation of power at frequencies of the order of 250 mc./s., and upward is at a low efficiency. The design requirements of the driving source are also less stringent if sine wave modulation rather than square wave modulation is used.

However, the main advantage obtained by the inclusion of active circuit elements, in the form of tunnel diodes, is the great increase in switching speed as compared with the conventional parametric circuit. The voltage appearing across the diodes when they are switched is determined by the diode characteristics. Consequently, the rise time is set simply by the time required for the amplitude of the sub-harmonic oscillation in the tuned circuit to stabilise with constant amplitude pulses applied to it. Correspondingly, the fall time is set by the rate at which the energy stored in the tuned circuit can be dissipated by the active elements. Thus, it is possible to achieve a complete switching cycle in, say, ten cycles of the driving waveform.

The circuit which has been described may be considered as having two stable states, since the single output may have either of two phases. It is possible to construct multi-stable arrangements in which multiple outputs are provided. In such an arrangement, three or more diodes are connected in series, and tuned circuits similar to that

formed by the inductors connected to form several series inductor pairs. The arrangement employing three such pairs will be considered as an example. It is exactly the same as the diode A corresponds to the first inductor in series correspondingly. The diode pair circuit is connected to the diode 3 and 4. The two conductors of the diode pair circuit may be connected to either phase may be connected to the output with either phase in the circuit.

It will be appreciated that convenient active elements may be described, since the manufacture and operation of such devices. However, the other devices, which may be of a generally similar form, may be used with a negative resistance.

The function of the capacitor 9 is simply to provide the desired frequency. It may equally well be replaced by capacitors and replace the inductor. In this form, a single inductor.

I claim:

1. An electrical logic circuit comprising a serially-connected pair of two terminal active circuit elements exhibiting a negative resistance characteristic having first and second positive resistance regions separated by a negative resistance element, the active elements being connected in series with current flow through said series circuit between said active elements; a series pair of inductors connected across said series circuit between said first and second positive resistance element connected in series with current flow through said first and second resistance regions, said first and second resistance regions forming a tuned circuit; means to apply an alternating driving voltage having a frequency substantially twice the resonant frequency of said tuned circuit, means to derive from said tuned circuit, which is at said resonant frequency, one or two phases which are relatively displaced by 180°; and means to apply to said first junction a signal to select the phase of said output signal.

2. An electrical logic circuit comprising a serially-connected pair of two terminal active circuit elements exhibiting a negative resistance characteristic having first and second positive resistance regions separated by a negative resistance region, said active elements being connected in series with current flow through said series circuit between said active elements; a first junction between said active elements; a series pair of inductors connected across said series circuit between the inductors of said pair; a capacitor connected between said first and second junctions; a series pair of inductors connected across said series circuit; means to apply an alternating driving voltage having a frequency substantially twice the resonant frequency of said tuned circuit, means to derive from said tuned circuit, which has, selectively, one or two phases which are relatively displaced by 180°; and means to apply to said first junction a signal to said first junction to select the phase of said output signal.

6. An electrical logic circuit, including a series circuit connected pair of similar two terminal active elements connected in the same sense for current flow through said series circuit and exhibiting, first and second positive resistance regions and a negative resistance region between said positive resistance regions; a series pair of inductors connected across said series circuit between said active elements; a capacitor connected across said inductors connected between said first and second junctions; a series pair of inductors together forming a tuned circuit; means to apply a uni-directional voltage across said series pair of active elements; means to apply to said serially-connected pair of active elements a driving signal having a frequency substantially the resonant frequency of the active elements to switch regions between said first and second junctions; means to produce an output signal by the switching of the active elements at said resonant frequency of two phases which are relatively displaced; and control means to apply to said signal to select the phase of

7. An electrical logic circuit, including a series circuit connected pair of similar tunnel diodes connected in the same sense for current flow through each diode exhibiting a current/voltage characteristic having first and second positive resistance regions and a negative resistance region between said positive resistance regions; a first junction between said diodes; means to apply a uni-directional voltage across said diodes to bias each diode in the same sense; a series pair of inductors connected between said first junction and said second junction, a second junction between said inductors; a capacitor connected between said first and second junctions; said inductors and said capacitor to form a tuned circuit; means to apply across said diodes an alternating driving voltage, having a frequency substantially twice the resonant frequency of said tuned circuit, to cause the diodes to switch repeatedly between said first and second positive resistance regions; means to produce an output signal in response to the switching of the diodes, said output signal having a frequency substantially the resonant frequency and having, selectively, one or two phases which are relatively displaced by 180°; and control means to apply to said first junction a signal to select the phase of said output signal.

8. An electrical logic circuit, including a serially-connected pair of similar tunnel diodes each having first and second electrodes, the first electrode of one diode being connected to the second electrode of the other diode at a first junction; a series pair of inductors coupled to said pair of diodes; a second junction between the inductors of said pair; a capacitor connected between said first and second junctions, said pair of inductors and said capacitor to form a tuned circuit; means to apply, by way of said pair of inductors, a voltage across the pair of diodes to bias each diode to substantially the same operating point, each diode exhibiting a current/voltage characteristic having first and second positive resistance regions and a negative resistance region between said positive resistance regions; means to apply across said diodes an alternating voltage of frequency substantially the resonant frequency of said tuned circuit to cause the diodes to switch repeatedly in opposite directions between said first and second positive resistance regions, causing oscillations in the tuned circuit; a signal coupled to said pair of inductors to produce a response to said oscillations, said signal selectively one of two phases depending upon which the diodes switch to said first junction.

positive resistance region; modulating means to modulate said alternating voltage to quench and restart said oscillations; and control means to select the phase of said output signals by applying to said first junction a signal to control said sequence.
